Primary Examiner—Melody N. Brown*Attorney, Agent, or Firm*—John F. Carroll IV[57] **CLAIM**

The ornamental design for a light support for rear of motorcycle, as shown.

DESCRIPTION

FIG. 1 is a perspective view of a light support for rear of motorcycle showing my new design; and,

FIG. 2 is a front elevational view thereof; and,

FIG. 3 is a rear elevational view thereof and,

FIG. 4 is a top plan view thereof; and,

FIG. 5 is a bottom plan view thereof; and,

FIG. 6 is a right elevational view showing my new design, the opposite being a mirror image thereof.
